(57) **CLAIM**

The ornamental design for a computer tablet holder, as shown and described.

DESCRIPTION

FIG. 1 is a top perspective view of a computer tablet holder showing my new design.

FIG. 2 is a bottom view thereof.

FIG. 3 is a front elevational view thereof.

FIG. 4 is a side elevational view thereof.

FIG. 5 is a top plan view thereof.

FIG. 6 is a bottom plan view thereof; and,

FIG. 7 is a view of the holder in place, attached to a tablet computer.

The front elevational view and back elevational view are identical. The left side elevational view and right side elevational view are identical.
